UNITED STATES PATENT OFFICE.

THOMAS J. BURTON, OF PLAINVIEW, MINNESOTA.

GATE.

Application filed May 7, 1924. Serial No. 711,660.

To all whom it may concern:

Be it known that THOMAS J. BURTON, a citizen of the United States, residing at Plainview, in the county of Wabasha and State of Minnesota, has invented certain new and useful Improvements in Gates, of which the following is a specification.

This invention relates to new and useful improvements in gates and more especially to stock and farm gates.

The primary object of my invention is to provide a gate of the type specified which is opened and closed by swinging the same up and down in a straight vertical plane as distinguished from the usual gate which is opened and closed by swinging horizontally.

Among the many advantages derived through the use of my invention, some of the more important may be briefly enumerated as follows:

First, the gate may be more easily and quickly opened and closed when properly balanced.

Second, the gate may be opened and closed with the minimum effort or exertion on the part of the operator.

Third, it is more advantageous for winter use by virtue of the fact that it is not necessary to remove snow from the ground adjacent the gate before opening or closing, as in the case of horizontally swinging gates, now commonly in use.

Fourth, my improved gate operates with equal facility regardless of whether the ground on opposite sides of the gate is smooth or uneven.

In the accompanying drawings which are for illustrative purposes only and are therefore not drawn to scale:

Figure 1 is a side elevation of a farm and stock gate embodying my improvements, the gate in lowered or closed position.

Figure 2 is a similar view, the gate open.

Figure 3 is a vertical transverse sectional view taken on line 3—3 of Figure 1.

Figure 4 is a horizontal section taken on line 4—4 of Figure 1.

Referring to the drawings for a more particular description of my invention and in which drawings like parts are designated by like reference characters throughout the several views, A designates the gate post and B my improved stock and farm gate, as a whole. At one end of the gate adjacent the post A, I provide an upright support C, consisting of a pair of laterally spaced parallel

boards 1 and 2, between which are received the adjacent ends of the longitudinal rails or bars 3, 4, 5 and 6, respectively, of the gate. The rails are pivotally connected together at their longitudinal centers, as at a, and at their outer ends as at b by the center brace 7 and outer gate bar 8. The bottom rail 3 is made somewhat shorter than the other rails as will be noted by reference to the drawings and more especially Figure 1, and is pivotally connected at its inner end by means of the cross pin 9 to the lower end of the support C.

The inner ends of the rails 4, 5, and 6 also work between the laterally spaced boards or members 1 and 2 of the support C and are pivoted as at 10 between the laterally spaced tines or members 11 of the forked bearing bracket 12 arranged in an upright position between the boards of the support C with its outer edges normally flush with those of the latter. A strand of barbed wire 13 is arranged in suitably spaced relation above the upper gate rails 6 and is connected with the upper ends of the bar 8 and center brace 7 and the upper end 14 of the forked bearing bracket 12, as indicated. Attention is invited to the fact that the inner ends of the gate rails 4 and 5 at their points of connection with the bearing bracket 12 are formed with longitudinal elongated slots 15 and 15' to provide the necessary play at these points in raising and lowering the gate.

A cable 17 is connected at one end, as 18, to the upper gate rail 6 at a point intermediate its ends but nearer the inner end of said rail and said cable extends over a pulley 19 carried by the bearing bracket 20, fastened to the top of the board or member 1 of support C. Said cable is connected at its opposite end as at 21 to the post A. A weight 22 provided at its upper end with a pulley 23 is supported by the cable 17 between the post A and support C and counterbalances the weight of the gate. This weight 22 is preferably in the form of a hollow cylinder filled with sand, as indicated more particularly in Figure 1.

In practice, the gate is opened and closed by swinging the outer end thereof straight up and down in a vertical plane upon the pivot or fulcrum 9.

When the gate is closed, the rails 3, 4, 5 and 6, thereof, are in parallel spaced relation but when the gate is opened, as illustrated in Figure 2, the rails are brought together in

contiguous relation and the ends of the rails disposed in stepped relation or one above the other. It will also be observed that as the gate is raised, the gate bar 8, center brace 7 and forked bearing bracket 12 are caused to assume an angle of approximately forty-five degrees. It will be understood of course, that the parts aforesaid assume their normal position when the gate is closed by swinging the same down in a straight vertical plane.

The outer ends 24 of the gate rails or bars 3, 4, 5 and 6 preferably extend somewhat beyond the outer gate bar 8 into a groove 25 in the fence post D, whereby the gate is held in position when closed.

From the foregoing description taken in connection with the drawings, it is thought that the construction, operation and advantages of my invention will be readily understood without requiring a more extended explanation.

Various changes in the form, proportions and minor details of construction may be re-

sorted to without departing from the principle or sacrificing any of the advantages of this invention as defined in the appended claim.

Having described my invention, what I claim as new and desire to secure by Letters Patent is:—

In combination with an upright support, a gate hinged thereto and adapted to be opened and closed by swinging straight up and down in a vertical plane, said gate comprising a shorter bottom rail pivoted at its inner end to the support and a plurality of longer vertically spaced top and intermediate rails pivotally connected together at their inner ends, a counterbalancing weight for said gate, and a forked bearing bracket to which the inner ends of the top and intermediate gate rails are pivoted.

In testimony whereof he affixes his signature.

THOMAS J. BURTON.
